US0D1103701S

(12) United States Design Patent (10) Patent No.: US D1,103,701 S
(45) Date of Patent: * Dec. 2, 2025

(54) BASKETBALL-THEMED BEVERAGE CONTAINER

(71) Applicant: Frost Buddy LLC, Newton, IL (US)

(72) Inventors: Mitch Mammoser, Newton, IL (US); Brock Mammoser, Newton, IL (US)

(73) Assignee: Frost Buddy LLC, Newton, IL (US)

() Term: 15 Years

(21) Appl. No.: 29/928,610

(22) Filed: Feb. 13, 2024

Related U.S. Application Data

(63) Continuation of application No. 29/820,388, filed on Dec. 21, 2021, now Pat. No. Des. 1,014,197.

(57) CLAIM

The ornamental design for a basketball-themed beverage container, as shown and described.

DESCRIPTION

FIG. 1 is a front view of a basketball-themed beverage container, showing our new design;

FIG. 2 is a right side view thereof, the left side view being identical thereto;

FIG. 3 is a top perspective view thereof;

FIG. 4 is a bottom perspective view thereof;

FIG. 5 is a top plan view thereof;

FIG. 6 is a bottom plan view thereof; and,

FIG. 7 is another bottom perspective view thereof.

The broken lines in the figures illustrate the portions of the basketball-themed beverage container that form no part of the claimed design.

1 Claim, 7 Drawing Sheets
